UNITED STATES PATENT OFFICE.

HENRY L. AMBLER AND WILLIAM AMBLER, OF CLEVELAND, OHIO.

DESIGN FOR A CLAMP.

SPECIFICATION forming part of Design No. 28,539, dated May 3, 1898.

Application filed March 5, 1897. Serial No. 626,140. Term of patent 7 years.

To all whom it may concern:

Be it known that we, HENRY L. AMBLER and WILLIAM AMBLER, citizens of the United States, residing at Cleveland, in the county of Cuyahoga, State of Ohio, have invented and produced a new and original Design for Clamps; and we do hereby declare the following to be a full, clear, and exact description of the same, reference being had to the accompanying drawings, forming a part thereof.

In the drawings, Figure 1 is a front view of a clamp illustrating our design, and Fig. 2 is an edge view.

As shown in the drawings, the upper por-

tion A of the clamp is flat, rectangular, with rounded corners *a a*. The outer end B is the arc of a circle, and the lower end C is curved reverse to the curve B.

The leading features of our design are those hereinbefore described.

What we claim is—

The design for a clamp, as herein shown and described.

HENRY L. AMBLER.
WILLIAM AMBLER.
